UNITED STATES PATENT OFFICE.

LAURENCE HAMMOND, OF SPANGLER, PENNSYLVANIA.

DYNAMITE BOX.

Application filed September 13, 1923. Serial No. 662,490.

To all whom it may concern:

Be it known that I, LAURENCE HAMMOND, a citizen of the United States, residing at Spangler, in the county of Cambria and 5 State of Pennsylvania, have invented certain new and useful Improvements in Dynamite Boxes, of which the following is a specification.

This invention relates to an improved box 10 for carrying dynamite and which, when constructed in reduced size, may also be employed for carrying caps and fuses.

The invention seeks to provide a strong 15 tight wooden box wherein nails or other metal parts will be absent.

The invention seeks, as a further object, to provide a box embodying interfitting joints throughout, so that moisture will be excluded.

20 And the invention seeks, as a still further object, to provide a box embodying a handle at one end thereof so that the box may be readily carried and wherein the door will be so arranged with respect to the handle and 25 the legs of the box that the door will be normally disposed to gravitate to closed position for maintaining the box closed.

Other and incidental objects will appear hereinafter.

30 In the drawing:

Figure 1 is a perspective view of my dynamite box;

Fig. 2 is a vertical sectional view taken medially through the device;

35 Fig. 3 is a transverse sectional view on the line 3—3 of Fig. 2, looking in the direction of the arrows, and

Fig. 4 is a detail sectional view on the line 4—4 of Fig. 2, looking in the direction of 40 the arrows.

In carrying the invention into effect, I embody a box body including side walls 10, top and bottom walls 11 and 12 and a back wall 13. The top and bottom walls are connected to the side walls by dovetail joints 14 while tongue and groove joints 15 are provided between the back wall and the side walls as well as between the back wall and the top and bottom walls. In this connection, it is to be noted that the grooves in the rear margins of the side walls open through the upper end edges of said walls so that the back wall may be assembled between said side walls by shifting the back wall downwardly therebetween, while the top wall 11 is, as particularly brought out in Fig. 2,

formed of mating sections comprising a relatively narrow rear section 16 assembled after the back wall is arranged in place, said section being of a width equal to the thickness 60 of the back wall and being grooved to accommodate the tongue at the upper edge of such wall. Closing the grooves in the side walls above the top wall 11 and below the bottom wall 12 are filler strips 16'. The side 65 walls are extended below the bottom wall to form legs 17 for the box body and are continued above the top wall to define spaced upstanding wings 18 preferably having curved upper edges. Extending between 70 said wings medially of the box body in spaced parallel relation to the top wall 11 is a handle 19 provided at its ends with reduced portions 20 projecting through said wings. Since the side walls 10 are held 75 against separation by the top and bottom walls, displacement of the handle will be prevented and, as will be seen, I provide a box body which is not only closed at the joints between the walls thereof but which will be 80 tight and exceedingly rigid. Formed in the side walls 10 at their forward margins are vertical grooves 20 and slidably between said walls is a door 21 provided at its longitudinal edges with tongues 22 fitting in said 85 grooves. At the upper ends of the grooves 20, the side walls are cut away, as indicated at 23, to facilitate the introduction of the tongues of the door into said grooves while at their lower ends, said grooves are closed 90 beneath the bottom wall 12 by filler strips 23'. Formed in the door near its upper end is a finger notch 24 defining a shoulder at the upper end of the notch for engagement to lift the door.

As previously intimated, the present box is formed entirely of wood and, as will now be seen, the door 21 will normally gravitate downwardly to rest at its lower edge against the bottom wall 12 for maintaining the box 10 closed while the legs 17 will serve to space the bottom wall from the ground and thus reduce the liability of moisture reaching the bottom wall. The handle 19 provides, of course, a convenient means of carrying 10 the box and attention is directed to the fact that a finger of the hand grasping the handle may be engaged in the notch 24 of the door for lifting the door when the other hand of the operator may be inserted beneath the door and employed to push the door upwardly and remove the contents of 11

the box. Thus, the box may be readily opened without the necessity for setting the box down or laying it on its side.

Having thus described the invention, what is claimed as new is:

1. A dynamite box including a box body having side walls continued to form legs extending beneath the box body as well as wings upstanding from the box body, a handle extending between said wings, and a vertically movable door gravitating to normally close the box body.
2. In a dynamite box, the combination of a box body having legs extending therebeneath, a horizontally disposed handle mounted above the box body, and a vertically movable door gravitating to normally close the box body, the upper end of the door being engageable by a finger of the hand grasping the handle for lifting the door.

3. In a dynamite box, the combination of an oblong box body having side walls continued at one end of the box body to form legs and also continued at the opposite end 25 of the box body to form upstanding wings, a handle extending between said wings, and a door slidably mounted upon the side walls to normally gravitate downwardly to closed position.

4. A dynamite box including a box body comprising side, back, top and bottom walls having interfitting jointed connection, the side walls being continued below the bottom wall to form legs and also being continued 30 above the top wall to form upstanding wings, a handle extending between said wings, and a door slideable upon the side walls and normally gravitating to close the box body.

In testimony whereof I affix my signature.
LAURENCE HAMMOND. [L. S.]
